UNITED STATES PATENT OFFICE.

ROBERT EDWIN REARDON, OF OTTAWA, ONTARIO, CANADA.

STRAINER.

1,247,006.

Specification of Letters Patent. Patented Nov. 20, 1917.

Application filed August 16, 1915. Serial No. 45,683.

To all whom it may concern:

Be it known that I, ROBERT EDWIN REARDON, of the city of Ottawa, Province of Ontario, Dominion of Canada, have invented 5 certain new and useful Improvements in Strainers, of which the following is the specification.

This invention relates to improvements in strainers such for example as are used 10 in sinks, and the objects of the invention are to provide a simple form of strainer which after using may be thrown away, may be manufactured in large quantities at low cost and which may be packed in a small 15 space when not used. More specific objects of the invention are to enable the strainer to be formed of a single flat blank of paper or like material, and to be so folded that it may support itself in position for use, and 20 it consists essentially of the improved construction hereinafter described in detail in the accompanying specification and drawings.

In the drawings:

25 Figure 1 is a perspective view of an embodiment of the invention, a portion of one side partly unfolded.

Fig. 2 is a plan view of the blank from which the strainer is formed.

30 Fig. 3 is a cross section through the strainer.

Fig. 4 is a view of a blank of different material from which the strainer may be formed.

35 In the drawings, like characters of reference indicate like parts in all the figures.

The strainer is formed of paper, pulp or similar material, it may in fact be formed of any material capable of being folded into 40 shape and whose value is such that it may be thrown away after a single use.

The strainer comprises a body portion 10 which forms the bottom of the strainer having two tabs 11 and 12 adapted to be 45 folded upwardly, and ends 13 and 14 also adapted to be folded upwardly. The ends and sides are adapted to interlock to form a receptacle above the body portion 10, said ends having a slight inclination toward the 50 body portion.

To effect the interlocking of the sides and ends, tabs 15 are provided on the ends having slots 16 to receive tongues 17 on the sides. The outer portions 18 and 19 of the 55 sides are adapted to be folded downwardly along lines of fold 20 and 21, their lower

edges being adapted to rest on a suitable base as for instance the sink, and support the strainer, they are splayed outwardly somewhat, from the portions 13 and 14 to 60 thereby form a better base, and they are also somewhat wider than the portions 13 and 14 in order that they will support the bottom portion 10 a distance above the base of the sink or other place in which they are 65 placed.

The portions 18 and 19 are formed on the sides with tabs 22, 23, 24, 25, the tabs 23 and 24 being adapted to interlock and the tabs 22 and 25 being adapted to interlock, 70 said tabs folding over the ends 11 and 12 as shown in Fig. 1 of the drawings, the interlocking being accomplished in any convenient way, as by the tongues 26 and 27 adapted to interlock in the respective slots 75 28 and 29.

The greater part of the body portion 10 and the inner side portions 13 and 14 are uniformly perforated, and the bottom edges of the portions 18 and 19 are serrated so 80 that it will form no obstruction to the material flowing through the strainer.

To reinforce the portions 18 and 19 which form the outer sides of the strainer when completely folded, reinforcing tabs 30 and 85 30 are formed on the bottom portion adapted to be folded inwardly flat against the inner side of the portions 18 and 19 as shown in Fig. 3 of the drawings.

The strainer may be formed of plain material as illustrated in Figs. 1 to 3, or of crimped material as shown in Fig. 4, the crimped material in some instances allowing the device to be made of lighter material by the fluting giving strength to the same. 95

What I claim as my invention is:

1. A self-contained paper garbage container and sink strainer, comprising a perforated body portion having upwardly foldable sides and upwardly foldable ends, said sides having downwardly turned portions provided with longitudinal extensions thereon, said extensions adapted to be folded inwardly and engage each other, said downwardly turned portions and extensions forming continuous outer supporting walls for the perforated body portion, substantially as described.

2. A foldable paper strainer comprising a body portion having upwardly foldable sides with tongues thereon, upwardly foldable ends having tabs with slots adapted to

receive the aforesaid tongues, said ends being formed with outer portions adapted to be folded downwardly to form supporting portions for the strainer, tabs on said downwardly foldable portions adapted to interlock with each other across the sides of the strainer.

In witness whereof I have hereunto set my hand in the presence of two witnesses.

ROBERT EDWIN REARDON.
